SHUTTER OR SIMILAR ARTICLE

Dana Loran Graham, Rte. 1, Box 378, Lenoir, N.C.

Filed Apr. 22, 1964, Ser. No. 79,659

Term of patent 3½ years

(Cl. D13—1)

FIGURE 1 is a plan view of the front of a shutter or similar article embodying my new design;

FIGURE 3 is a plan view of the front of a modified form of shutter or similar article embodying my new design.

The rear portion of each shutter or similar article shown in FIGURES 1 through 3 of the drawings is substantially plain and unornamented.

I claim:

The ornamental design for a shutter or similar article, substantially as shown and described.
